DELAYED-ACTION ELECTRIC SWITCH

Ralph L. Wells, Dunedin, Fla.; Tilton S. Wells
executrix of said Ralph L. Wells, deceased

Application January 3, 1950, Serial No. 136,599

1 Claim. (Cl. 200—33)

1

This invention relates to delayed action electric switches and more particularly to a house type switch which will act to extinguish a light with which it is connected a predetermined time interval after the switch has been manually operated to off position.

It is among the objects of the invention to provide an improved delayed action, manually operated switch which will open a circuit into which it is connected a predetermined time interval after the switch has been manually operated from closed to open position, and can be manually operated to open the circuit immediately, if desired, which will fit into an existing switch receptacle without modification of the receptacle and can be connected into a conventional house wiring system, which is positive in action and entirely safe in use, and which is simple and durable in construction, economical to manufacture, and not subject to malfunctioning in use.

Other objects and advantages will become apparent from a consideration of the following description and the appended claim in conjunction with the accompanying drawings wherein:

Figure 1 is a side elevation of a switch illustrative of the invention;

Figure 2 is a top plan view of the switch illustrated in Figure 1;

Figure 3 is a cross sectional view of the switch on the line 3—3 of Figure 1;

Figure 4 is a cross sectional view of the switch on the line 4—4 of Figure 2 and looking in the direction of the arrows;

Figure 5 is a cross sectional view on the line 5—5 of Figure 2 and looking in the direction of the arrows;

Figure 6 is a cross sectional view on the line 6—6 of Figure 3;

Figure 7 is a cross sectional view on the line 7—7 of Figure 6;

Figure 8 is a cross sectional view on the line 8—8 of Figure 3; and

Figure 9 is a cross sectional view on the line 9—9 of Figure 6.

With continued reference to the drawings, the delayed action switch comprises a hollow switch housing 10 of generally rectangular shape having spaced apart, substantially parallel side walls 11 and 12, spaced apart, substantially parallel end walls 13 and 14 and a bottom wall 15. The switch housing is open at its top side and is covered at this open side by a cover plate 16 having at its opposite ends apertured tabs 17 for securing the switch in a switch receptacle.

A U shaped yoke 18 is pivotally mounted at its

open end on the side walls of the switch housing 10 near the open side and substantially at the mid-length location of the switch housing and extends transversely of the hollow interior of the housing. This yoke 18 is movable between spaced apart stops 19 and 20 from a switch closing position, as illustrated in Figure 4, in which it is against the stop 19 to a switch opening position in which it is against the stop 20.

10 A manually operated toggle lever 21 is pivotally mounted in the switch housing near the open side and substantially at the mid-length location of the housing and extends outwardly of the housing through an elongated aperture 22 in the cover 16. A coiled toggle spring 23 is compressibly disposed between the closed bottom end of the yoke 18 and the inner side of the toggle lever 21 and is effective to swing the toggle yoke 18 between its switch opening and switch closing positions as the manually operated toggle lever 21 is moved between its switch opening and switch closing positions.

The end walls 13 and 14 are apertured near the bottom wall 15 and a contact plate 24 is mounted at the inner side of the end wall 13 and is provided with an aperture receiving a terminal screw 25 by means of which an electrical conductor 26 is secured to and electrically connected to the plate 24.

25 30 A similar contact plate 27 is mounted within the end wall 14 and provided with an aperture for a terminal screw 28 which secures and electrically connects the conductor 26 to the contact plate 27. The contact plate 24 has an inwardly projecting contact finger 30 thereon and the contact plate 27 is provided with a similar inwardly projecting contact finger 31.

35 40 A metal disc 32 is pivotally mounted on the inner side of the side wall 11 of the switch housing 10 substantially coaxially with the pivotal connection between this side wall and the toggle yoke 18 and a switch arm 33 is secured to this disc 32 and rotatable therewith. In one position of the disc the switch arm 33 engages at its opposite ends the two contact fingers 30 and 31 and provides an electrical connection between these fingers thereby closing the switch and in another position of the disc 32 the switch arm 33 is out of contact with the fingers 30 and 31 thereby opening the switch, the two positions of the disc 32 corresponding to the "on" and "off" positions of the switch yoke 18, as explained above.

45 50 A stud 34 is provided on the disc 32 and is engaged by the yoke 18 when the yoke moves from its switch opening to its switch closing posi-

tion to rotate the disc 32 in a switch closing direction and bring the arm 33 into connecting engagement with the fingers 30 and 31. The disc 32 is provided adjacent the stud 34 with a peripheral notch 35 and a lever 36 pivotally mounted intermediate its length on the side wall 11, as indicated at 37, has on one end a lug 38 which engages in the notch 35 to hold the disc 32 against rotation in its switch opening direction. A leaf spring 39 secured to the side wall 11 of the switch housing contacts the outer side of the lever 36 and resiliently holds the lug 38 engaged in the notch 35.

A first shaft 40 extends transversely of the interior of the switch housing and is journaled at its ends in the end walls 11 and 12 or, if desired, in metal liners 41 and 42 disposed adjacent the inner sides of the housing side walls 11 and 12 and in which the yoke 18, the disc 32 and the lever 21 may also be journaled. A two lobed cam 43 is secured on the shaft 40 and engages the lever 36 at the end of the lever opposite the lug 38. Angularly spaced apart studs 44 project from one side of this cam and a rod 45 pivotally connected at one end to the yoke 18, as indicated at 46, has on its opposite end a detent 47 which progressively engages the studs 44 and rotates the cam 43 through one quarter of a revolution each time the toggle yoke 18 is moved from its switch closing to its switch opening position. When the yoke is moved from its switch opening to its switch closing position the detent 47 engages the next stud on the cam. The rod is supported intermediate its length in a guide 48 and is resiliently held in stud engaging position by a leaf spring 49 secured to the inner side of the side wall 11 of the liner 41.

With the arrangement so far described, if the manually operated lever 21 is moved from its switch closing to its switch opening position once, the lug 38 engaging in the notch 35 in the disc 32 will prevent the disc from rotating to move the switch arm 33 out of engagement with the contact fingers 30 and 31. However, if the toggle lever be immediately moved to its switch closing position and back to its switch opening position the cam 43 will be rotated through an additional one quarter revolution by the rod 45 and detent 47 and one of its lobes will engage the lever 36 and move the lug 38 out of the notch 35 thereby freeing the disc 32 to rotate to its switch opening position. Rotation of the disc to its switch opening position is provided by a spring 50 which connects the yoke 18 to the disc in such a manner that the yoke can move to its switch opening position without rotating the disc but will spring bias the disc to move to its switch opening position as soon as the disc is freed from the lug 38.

A second disc 51 is rotatably mounted on the side wall 12 or on the metal liner 42 coaxially with the pivotal connection between this liner and the yoke 18 at the open end of the latter, and a spring 52 connects this disc to the yoke in such a manner that the yoke can move to its switch opening position without rotating the disc but the spring will be tensioned thereby to rotate the disc 51 through a predetermined angular extent. This disc 51 is provided with peripheral gear teeth 53 for driving the escapement mechanism which delays the opening action of the switch for a predetermined time interval after the toggle lever 21 has been moved to its switch opening position.

A second shaft 55 extends transversely of the interior of the switch housing adjacent the shaft 40 and is journaled at its ends in the side walls

of the housing or the liners 41 and 42. A gear 56 freely rotatable on the shaft 55 has teeth which mesh with the teeth on the disc 51 and a second gear 57 rotatably mounted on the shaft 55 meshes with a lantern gear 54 mounted on shaft 40. A third shaft 58 extends transversely of the interior of the switch housing adjacent the shaft 55 and is journaled in the housing side wall or the liner 42 and an escapement gear 59 is mounted on this shaft. A pin gear 60 is also mounted on the shaft 58 and secured to the escapement gear 59 and a gear 61 freely rotatable on the shaft 55 meshes with the gear 60.

A balance wheel 62 is mounted on the shaft 40 and is driven by a hair spring 63 and a pallet lever 64 pivoted on the shaft 55 carries pallets engaging the escapement wheel 59 and is operated by the balance wheel 62 through the connection 65. A ratchet pawl 66 carried by the gear 56 engages with the teeth of the gear 61 and a ratchet pawl 67 carried by the gear 61 engages the teeth of the gear 57, both ratchet pawls being operative in the same direction so that the three gears 56, 61 and 57 are driven together in one direction of rotation.

The gears 56, 61 and 57 are locked together for simultaneous rotation in the direction in which they are driven by the spring 52 through the toothed disc 51 when the yoke 18 is moved to its switch opening position. The force of the tensioned spring 52 acting on the disc 51 under these conditions drives the gear assembly including the gears 56, 61 and 57 and this gear assembly in turn drives the gears 54 and 60. The speed of rotation of the gear 60 is regulated by the operation of the pallet lever 64 and balance wheel 62 and regulates the speed of rotation of the gear 54 which rotates the cam 43.

The lantern gear 54 has two separate groups of pin teeth and when it has been rotated an amount sufficient to rotate the cam 43 through one quarter of a revolution its pin teeth come out of mesh with the teeth of the gear 57 so that the spring 52 can run down without imparting any further rotation to the gear 54 or the cam 43. When the cam 43 is moved through this additional one quarter revolution it operates the lever 36 and releases the disc 32 to move the switch arm 33 to switch opening position.

When the toggle lever is moved to switch closing position the cam is rotated through one quarter of a revolution, as explained above, and the disc 51 will also be rotated by engagement of the yoke 18 with the stud 68 on this disc. The ratchet pawls 66 and 67 permit the disc 51 to move in this direction without rotating the gears 61 and 57 or the gears 60 and 54. The first one quarter rotation of the disc 43 by the rod 45 will, however, rotate the gear 54 to a position in which the forward end of one series of pin teeth of this gear is in position to mesh with the teeth of the gear 57 so that the gear 54 will be rotated through one quarter of a revolution upon the next movement of the toggle lever to its switch opening position.

The time interval between the moving of the toggle lever 21 to switch opening position and the further rotation of the cam 43 to free the disc 32 for opening the switch is determined by the construction of the escapement mechanism and may be regulated to some extent by adjusting the hair spring 63. It has been found that a time interval of approximately one minute is ordinarily sufficient to permit a person to turn off one

switch and safely reach another switch or to leave the house.

The invention may be embodied in other specific forms without departing from the spirit or essential characteristics thereof. The present embodiment is, therefore, to be considered in all respects as illustrative and not restrictive, the scope of the invention being indicated by the appended claim rather than by the foregoing description, and all changes which come within the meaning and range of equivalency of the claim are, therefore, intended to be embraced therein.

What is claimed is:

A delayed action manually operated switch comprising a hollow housing having an open side, a yoke disposed in said housing and pivotally connected at its open end to said housing at the open side of the latter, a toggle lever pivotally mounted in said housing and projecting from the open side of the latter, a cover secured to the open side of said housing for maintaining said yoke and said lever in operative assembly with said housing and having an aperture through which said lever extends, a toggle spring disposed between said lever and said yoke for swinging said yoke from one to the other of its two terminal positions when said lever is manually moved between its switch opening and switch closing positions, two discs disposed within and rotatably mounted on said housing one at each side of the housing and both adjacent said yoke, one of said discs having a peripheral notch therein and the other having peripheral gear teeth thereon, a pair of contacts in said housing disposed one at each end of the latter, a switch arm carried by one disc and movable by rotation of said one disc in one direction into engagement with said contacts to close the switch, a stud on each of said two discs, such studs being engaged by said yoke when moving to its switch closing position to impart switch closing rotation to said one disc and similar rotation to said other disc, a first shaft extending transversely across said housing, a two lobed cam and a gear secured on said shaft, angularly spaced apart studs on said cam, a rod pivotally secured at one end to said yoke and having on its opposite end a detent engageable with the studs on said cam to rotate said cam through one fourth of a revolution each time said
